ATTORNEY

UNITED STATES PATENT OFFICE.

CHARLES J. PILLING, OF PHILADELPHIA, PENNSYLVANIA, ASSIGNOR TO
GEORGE P. PILLING AND CHARLES J. PILLING, OF SAME PLACE, (CO-
PARTNERS TRADING AS GEO. P. PILLING & SON.)

DESIGN FOR A BLANK FOR SPECULA.

SPECIFICATION forming part of Design No. 34,337, dated April 9, 1901.

Application filed February 9, 1901. Serial No. 46,744. Term of patent 7 years.

To all whom it may concern:

Be it known that I, CHARLES J. PILLING, a citizen of the United States, residing at the city of Philadelphia, State of Pennsylvania, have invented and produced a certain new and original Design for a Blank for a Speculum, of which the following is a full, clear, and exact description, reference being had to the accompanying drawings, forming a part of this specification.

In the drawings, Figure 1 is a plan view, and Fig. 2 a side view, of the blank.

My invention consists of the design, in novel external planular shape or configuration shown, of the sheet-metal blank from which a vaginal speculum is produced.

Commencing at the top of the illustrations

in the drawings, the side lines of the speculum diverge with a gradually-increasing divergence, then converge for a short distance and again diverge, the outline from the last point of divergence to the bottom of the blank being concaved and the side lines being joined. 20

I claim—

The design for a blank for a speculum substantially as shown and described. 25

In testimony whereof I have hereunto affixed my signature this 18th day of January, A. D. 1901.

CHARLES J. PILLING.
